UNITED STATES PATENT OFFICE.

JOHN R. FREEMAN, OF BUFFALO, NEW YORK, ASSIGNOR TO AMERICAN RADIATOR COMPANY, OF NEW YORK, N. Y., A CORPORATION OF NEW JERSEY.

MOLDING APPARATUS.

Application filed September 16, 1924. Serial No. 737,966.

My invention relates broadly and generally to new and useful improvements in molding apparatus, and more particularly of that type in which a sand mold is formed by a suitable pattern for the casting of metallic objects.

In the art to which the invention relates, it is the practice to form a sand mold by properly positioning a flask member, i. e., the cope or the drag in relation to a pattern, packing the sand in said member so as to conform to the pattern, and then assembling the flask members so as to match the sand mold parts contained therein. In this practice it is usual to provide guide means for properly holding or positioning the flask element relative to the pattern, and also for locating the cope and drag in assembled relation to each other so that the sand mold sections or parts will properly match. It sometimes occurs that through inaccuracy of the parts, or expansion or contraction of the metallic flask elements, the usual guide means employed will not cause the coacting elements to properly register or match, and it is therefore the primary object of the invention to provide a guide means readily applicable to either a pattern member, or a flask member, to automatically compensate for such inaccuracy or expansion or contraction that the parts when assembled will be in proper relation to each other.

The invention consists in the improved construction of parts and their aggroupment in operative combination, to be more fully described hereinafter, and the novelty of which will be particularly pointed out and distinctly claimed.

In the accompanying drawings to be taken as a part of this specification, I have fully and clearly illustrated a preferred embodiment of my invention, and in which—

Figure 1 is a view in vertical longitudinal central section through a structure showing the invention in an embodiment for properly guiding or holding a flask member relative to a pattern member while a sand mold is being formed in the flask member.

Fig. 2 is an enlarged view, partly in section, of the embodiment of the invention shown in Fig. 1;

Fig. 3 is a detail top plan view of the construction shown in Fig. 2.

Before proceeding with a detailed description of the preferred embodiment

shown, I would state that while the invention is shown as applied to a pattern stand or support, it is with equal facility and without essential change applicable to a mold part or section, for example the drag, so as to properly locate the cope with relation thereto. Therefore, I wish it understood that my invention is not limited to application to a pattern stand, but to include association with the elements of cooperating mold members.

Referring to the drawings, 1 designates, generally, a pattern stand or support, which may be of any well known or suitable construction. The stand supports on its upper portion a horizontal table or platform 2, having at its opposite ends lugs or projections 3, 4, for a purpose to be presently described. Supported on, and suitably connected to the table 2, is a horizontally disposed pattern plate 5, having on its upper surface any suitable form of pattern 6, the configuration of which is to be imparted to the sand mold to be formed. At its ends the pattern plate is provided with projections or lugs 7, 8, which respectively overlie the projections 3 and 4 heretofore described.

Supported at one end of the stand, for example by the lugs 3 and 7, is a guide pin 9, which may, if desired, but not necessarily, be of a well known fixed type. In the present embodiment the pin 9 includes an upper frustro-conical portion 10, a cylindrical holding portion 11, having a shoulder resting on the upper face of the lug 7, and said pin having a threaded shank 12, which projects through openings or slots in the lugs 7 and 3, and receives at its lower end below lug 3, a clamping nut 13, by which the pin is clamped rigidly in position. At its opposite end from the pin 10, the molding element, for example the stand, or pattern plate, is provided with the automatically adjustable guiding or positioning device constituting my invention, which will now be described:

The lugs or projections 4 and 8 are provided respectively with longitudinally extending through slots 14, 15, which align vertically with each other, and the corresponding side walls of which lie in the same vertical plane, said slots being closed at their inner ends, as at 16, 17. Arranged in these slots 14, 15, is a guide element in the form of a pin 18, having an upper frustro-conical

portion 19 and a cylindrical holding portion 20 located above the lug 8, and at the base of which is an annular shoulder 21. Beneath the shoulder 21 said pin is formed with a cylindrical portion 22 located within the slots 14 and 15, and of less diameter than the width of said slots, while at its lower end the pin is formed with a threaded shank 23 projecting below the lower face of the lug 4.

Rigidly mounted on the pin part 22 is a bushing 24 having opposite flat faces 25 parallel to each other and adapted to closely but slidably engage the inner faces of the side walls of the slots 14, 15. By this arrangement the guide pin 18 may slide laterally of itself in the slots 14, 15, and may also rock therein, as will more fully appear hereinafter. The bushing is preferably secured in place by a press-fit on the cylindrical part 22.

Upon the cylindrical part 22 and abutting the shoulder 21, is a friction plate 26, preferably in the form of a metallic washer which lies upon the upper horizontal face of the lug 8, and on the lower end portion of the pin is a friction plate 27, preferably in the form of a washer which is arranged in engagement with the under face of the lug 4. On the lower end of the shank or portion 23 of the pin, is adjustably threaded a stop collar or nut 28, between which and the plate 27, is disposed a coiled spring 29 surrounding said shank, and which exerts its force expansively against said plate and collar to maintain plate 26 in strong frictional engagement with the lug 8, and the plate 27 in strong frictional engagement with the lug 4. The collar may be held in adjusted position by means of a cotter-pin 30 extending through said collar, and a suitably located transverse opening 31 in the pin 18. By this arrangement the pin 18 will be held in vertical position relative to said lugs, but at the same time can be moved lengthwise of the slots, in a manner to be presently described.

The outer open ends of the slots 14, 15 are closed by suitable means, preferably in the form of a filler piece 32 of yielding material, such as block felt closely fitting said slots and held in place by a split pin 33 let through openings 34 in the lug 4 and said filler. This piece not only limits outward movement of the pin 18, but also prevents sand from collecting in the slots 14, 15.

As heretofore stated, I have shown the invention as applied to a pattern stand upon which flask parts are placed when the sand mold is to be formed, and in Fig. 1, I have shown a flask part in the position assumed thereby when mounted on the stand. In this figure the flask 35 is of a standard rectangular form, having end walls 36, and apertured guide or positioning lugs 37, the

apertures of said lugs receiving or setting over the pins 9 and 18 when the flask is in position on the stand for making of the mold. It will be readily understood that in a foundry of large capacity where many flasks of the type mentioned are employed, and are to be supplied with said molds at the same pattern stand, that due to variations in distance between the lugs 37 for any reason, for example because of heat expansion, if the pins 9 and 18 were fixed, the flasks could not be placed on the stand, or could not be properly positioned thereon relative to the pattern, as the distance between centers of the openings in lugs 37 might not permit the openings to properly receive the pins. This objectionable condition is overcome by my invention, because when the aperture in lug 37 is placed over the pin 18, the latter will be automatically moved to take such position that the flask may be moved down into proper position on the pattern stand. For example, in the event a flask is brought to the pattern stand for the mold making, and the distance between centers of the openings in the lugs 37 is less than the distance between the pins 9 and 18, when one of the lugs is adjusted on the pin 9, and the other lug is placed on pin 18, the outermost face of the aperture in said last-named lug will strike against the outermost face of the inclined part 19, which will move the upper end of pin 18 inward toward the left of Figs. 1 and 2, the part 22 rocking or canting over in its bearing. When the flask part is moved farther down, the pin is moved over until the outermost part of the opening in lug 37 reaches the cylindrical part 20, whereupon the pin will be straightened up and hold the flask part in proper position.

If the distance between centers of the openings in the lugs 37 is greater than the distance between the pins, the opposite result takes place—that is, the innermost face of the aperture in lug 37 engages the innermost face of the conical part 19, and the pin 18 is moved outward in a manner which is readily understood from the above. It will be apparent that the yielding friction connection between the pin 18 and the molding element on which it is mounted, permits movement of the pin as described, and also holds the pin in proper adjusted position to which it may be moved. By this means the pin is automatically adjusted by engagement of the cooperating mold element therewith, and no attention on the part of the operators is normally necessary. However, the pin may be adjusted manually and will retain its adjusted position without the necessity of loosening and reengaging any parts.

What I claim and desire to secure by Letters Patent of the United States is:

1. In a molding apparatus of the character

- ter described, a molding element, a guide pin mounted thereon for lateral movement by engagement of a cooperating molding element therewith, and yielding friction means permitting such movement and holding said pin in a position to which it may be moved.
2. In a molding apparatus of the character described, a molding element provided with a projection, a guide pin mounted on said projection for lateral movement by engagement of a cooperating molding element therewith, and yielding friction means carried by said pin and engaging said projection.
3. In a molding apparatus of the character described, a molding element provided with a projection, a guide pin mounted on said projection for lateral movement by engagement of a cooperating molding element therewith, and yielding means maintaining said friction means in engagement with said projection.
4. In a molding apparatus of the character described, a molding element provided with a projection, a guide pin mounted on said projection for lateral movement by engagement of a cooperating molding element therewith, and yielding friction means carried by said pin and movable longitudinally thereof and engaging said projection.
5. In a molding apparatus of the character described, a molding element provided with a projection, a guide pin mounted on said projection for lateral movement by engagement of a cooperating molding element therewith, a friction plate carried by said pin, and means for yieldingly maintaining said plate in engagement with said projection.
6. In a molding apparatus of the character described, a molding element provided with a projection, a guide pin mounted on said projection for lateral movement by engagement of a cooperating molding element therewith, a friction plate carried by said pin, and a spring on said pin for yieldingly maintaining said plate in engagement with said projection.
7. In a molding apparatus of the character described, a molding element provided with a projection, a guide pin mounted on said projection for lateral movement by engagement of a cooperating molding element therewith, a friction plate carried by said pin, an abutment on said pin, and a spring between said abutment and plate for yieldingly maintaining said plate in engagement with said projection.
8. In a molding apparatus of the character described, a molding element provided with a projection having an opening, a guide pin carried by said projection and laterally movable in said opening by engagement of a cooperating molding element therewith, and a bushing on said pin and slidably fitting said slot, and yielding friction means carried by said pin and engaging said projection.
9. In a molding apparatus of the character described, a molding element provided with a projection having a slot, a guide pin carried by said projection and laterally movable in said slot by engagement of a cooperating molding element therewith, a bushing on said pin and slidably fitting said slot, and yielding friction means carried by said pin and engaging said projection.
10. In a molding apparatus of the character described, a molding element provided with a projection having a slot, a guide pin extending through said slot, said pin having a shoulder, a plate on said pin and engaging one side of said projection and held in such engagement by said shoulder, a second plate movable on said pin and engaging the opposite side of said projection, and spring means holding said second plate in yielding engagement with said projection.
11. In a molding apparatus of the character described, a molding element provided with a projection having an opening, a guide pin carried by said projection and laterally movable in said opening by engagement of a cooperating molding element therewith, said pin having a shoulder, a plate on said pin and engaging one side of said projection and abutting said shoulder, a second plate movable on said pin and engaging the opposite side of said projection, an abutment on said pin, and a spring between said abutment and plate for yieldingly maintaining said second plate in engagement with said projection.
12. In a molding apparatus of the character described, a molding element provided with a projection having an opening, a guide pin carried by said projection and laterally movable in said opening by engagement of a cooperating molding element therewith, said pin having a shoulder, a plate on said pin and engaging one side of said projection and abutting said shoulder, a second plate movable on said pin and engaging the opposite side of said projection, an abutment threaded on said pin, and a spring between said abutment and plate for yieldingly maintaining said second plate in engagement with said projection.
13. In a molding apparatus of the character described, a molding element provided with a projection having an open-ended slot, a guide pin mounted for lateral movement in said slot by engagement with a cooperating molding element, yielding friction means carried by said pin and engaging said projection, and a filler closing the open end of said slot and limiting movement of said pin.
14. In a molding apparatus of the character described, a molding element provided with a projection having an open-ended slot, a guide pin mounted for lateral movement

in said slot by engagement with a cooperating molding element, yielding friction means carried by said pin and engaging said projection, and a filler of compressible material closing the open end of said slot and limiting movement of said pin.

15. In a molding apparatus of the character described, a molding element provided with a projection having an open-ended slot, a guide pin mounted for lateral movement in said slot by engagement with a cooperat-

ing molding element, yielding friction means carried by said pin and engaging said projection, a filler of compressible material closing the open end of said slot and limiting movement of said pin, and a pin extending through said projection and filler to hold the latter in position. 15

In testimony whereof I have hereunto subscribed my name.

JOHN R. FREEMAN.
